UNITED STATES PATENT OFFICE.

ANDRÉ LAVAULT, OF PARIS, FRANCE, ASSIGNOR TO ASSOCIATED MERCHANTISING CORPORATION, A CORPORATION OF NEW JERSEY.

DESIGN FOR A BOTTLE FOR PERFUME OR THE LIKE.

Application filed November 25, 1927. Serial No. 24 274. Term of patent 14 years.

To all whom it may concern:

Be it known that I, ANDRÉ LAVAULT, a citizen of France, and a resident of Paris, France, have invented a new, original, and ornamental Design for Bottle for Perfume or the Like, of which the following is a specification, reference being had to the accompanying drawing, forming part thereof.

In carrying out my design, the body of the bottle is slightly clouded and translucent, the neck is wound with gold cord and the stopper is of a green color.

I claim:

The ornamental design for a bottle for perfume or the like, as shown and described.

A. LAVAULT.
